UNITED STATES PATENT OFFICE

2,568,143

SPIRIT LEVEL

Edward J. Casper, Bronx, N. Y.

Application November 20, 1947, Serial No. 787,054

1 Claim. (Cl. 33—212)

1

This invention relates to spirit levels as used by mechanics to designate level, plumb, square and miters in work being performed or constructed. More particularly, the invention deals with a device of this kind employing a spirit element of octagon form, whereby readings may be taken in all positions of the level. Still more particularly, the invention deals with a device of the character described wherein the mounting of the spirit element in the level or tool is simplified. Further, wherein the spirit element is composed of two similar parts secured together.

The novel features of the invention will be best understood from the following description when taken together with the accompanying drawing, in which certain embodiments of the invention are disclosed and in which the separate parts are designated by suitable reference characters in each of the views, and in which:

Fig. 1 is a side view of a part of a spirit level or similar tool showing one of my improved devices therein.

Fig. 2 is a section on the line 2—2 of Fig. 1; and

Fig. 3 is an enlarged face view of a spirit element with part of the construction broken away.

In Figs. 1 and 2 of the drawing, I have shown at 10, part of the stock of a spirit level tool. This stock is provided at a suitable position therein with a round center bore 11 in which the spirit element 12 is adapted to be mounted. At each side of the bore 11 are recesses 13—13' in which are arranged bevelled rings 14—14'. The rings 14—14' are of less inside diameter than the diameter of the bore 11 so as to overlie side surfaces of the element 12, as clearly seen in Fig. 2 to bring parallel spirit markings, as at 15, Fig. 1, into close proximity to the spirit bubble 16 of the element 12, as is clearly illustrated in Fig. 1 of the drawing. In this connection the fluid of the spirit element 12 has been omitted from Fig. 2 for sake of clarity. It will be understood that markings similar to the markings 15 are also arranged upon the ring 14', part of which is seen at 15' in Fig. 2.

Beyond the recesses 13—13', the stock 10 is also preferably bevelled or flared outwardly, as seen at 17—17'. The element 12 is composed of two similar octagon discs 18—18'. Two of the surfaces of the discs are adapted to be arranged parallel with the side edges of the stock 10 and two other surfaces at right angles to the first surfaces are disposed at right angles to the side edges of the stock, as will clearly appear in Fig. 2

5 arranged about the bore 11 so as to overlap the side edges of the stock 10, as seen in Fig. 1. The bevelled corners 12' of the element 12 are disposed to fit within the recesses 13—13' in the stock 10, as shown in Fig. 2. Before the element 12 is secured in the bore 11, the rings 14—14' are arranged in the recesses 13—13' and the element 12 is secured in the bore 11, the element 12 being secured in the bore 11 by any suitable means, such as cement, adhesive, or the like.

10 The element 12 has recesses 20—20' on the inner surfaces of the separate parts thereof which generally conform in contour to the octagon peripheral shape of the parts 18—18'. However, these octagon surfaces, shown at 21—21' in Fig. 3 of the drawing are convexly curved to a slight extent to facilitate positioning of the spirit bubble 16 centrally of these surfaces in taking a reading. Adjacent surfaces of the parts 18 and 19 beyond the recesses 20—21' abut and are secured together by any suitable adhesive consistent with and suitable for use in conjunction with the material employed in forming the parts 18—18'. Here it is to be understood that these parts may be molded or otherwise formed from glass or transparent plastic materials. In this connection it will also be understood that the rings 14—14' may be composed of wood, metal or plastic material and when plastic material is employed, they may be of an opaque or translucent structure.

15 With a spirit level of the type and kind under consideration, readings may be taken in any position of the tool for gauging, level or plumb readings, or for gauging miter or forty-five degree readings, thus providing what may be termed a universal spirit level tool. It will be apparent that my improved spirit element may be mounted in stocks of any type or kind, and while in most instances a single spirit element will be sufficient in each tool, in some instances, it may be desirable to arrange two of the elements in a tool, particularly where the stock is relatively long.

20 Having fully described my invention, what I claim as new and desire to secure by Letters Patent is:

25 In spirit level devices, a stock, said stock having an aperture of predetermined diameter therein, the stock, at opposed sides of the aperture, having enlarged annular recesses, a spirit element

mounted in the aperture of the stock between said recesses, said element comprising two substantially similar discs of octagon form, adjacent surfaces of the discs having recesses bounded by octagon walls, said walls being convexed outwardly to a slight extent and otherwise substantially paralleling the outer edges of the disc structure, parts of said elements being secured together to form, within the recesses thereof, a chamber for spirit fluid, including a bubble, bevelled facing rings mounted in the recesses and overlying outer peripheral portions of the spirit element outwardly of and adjacent the walls of the chamber therein in retaining said element in the aperture of the stock, at least two opposed edges of the element being parallel to opposed edges of said device, side surfaces of the stock outwardly of said recesses, being bevelled to register with the bevelled faces of the rings, and said rings having markings registering with each 15 of the convex walls of said element.

EDWARD J. CASPER.
